UNITED STATES PATENT OFFICE.

WILLIAM N. REED, OF HACKENSACK, NEW JERSEY.

JARDINIÈRE.

1,177,055.

Specification of Letters Patent. Patented Mar. 28, 1916.

Application filed May 25, 1915. Serial No. 30,369.

To all whom it may concern:

Be it known that I, WILLIAM N. REED, a citizen of the United States, residing at Hackensack, in the county of Bergen and State of New Jersey, have invented new and useful Improvements in Jardinières, of which the following is a description.

My invention relates to jardinières of the kind having a compartment for holding a flower pot or a charge of soil, as the case may be, in order to support and display living flowers or plants and to facilitate watering the same.

One purpose of my invention is to provide the jardinière with a drip pan, housed within the base of the jardinière, and adapted for receiving any excess of water percolating through the flower pot or through the charge of soil.

Another purpose of my invention is to give such form to the jardinière and parts immediately associated with it that under ordinary conditions the drip pan is concealed from casual observation, and yet at any desired moment may be inspected, or easily removed and emptied without the necessity for lifting any heavy part or disturbing the flowers or plants.

Reference is made to the accompanying drawings forming a part of this specification, and in which like letters indicate like parts.

Figure 1 is a perspective of a small jardinière containing a flower pot and equipped with my invention, the parts here being in normal position. Fig. 2 is a view, partly in section and partly broken away, showing the same jardinière, the movable parts appearing in full lines as occupying their normal positions, and in dotted lines as moved into their abnormal positions. Fig. 3 is a fragmentary elevation showing the lower portion of the metallic container in the bottom of which the drip pan is normally housed. Fig. 4 is a view, partly in section and partly broken away, showing a jardinière of larger form than the one appearing in Figs. 1 and 2, and also indicating, by dotted and full lines, the movements of the drip pan and the concealing band for normally hiding the same. Fig. 5 is a view, partly in section and partly broken away, showing a still larger jardinière with a detachable base, this view indicating by dotted lines the movement of the concealing band.

Resting upon a support 6, which may be a table or a window ledge, is a metallic container 7, having substantially the form of a cone frustum, and provided with a base 8, serving as a bottom and made in this instance of wood. The base is held in position by fastenings, one of which is shown at 7^a. The container is also provided with a floor 9, spaced from the bottom 8 and located parallel therewith, this floor having a funnel shaped vent 10. The container is cut away so as to form an opening 11, which is located below the floor 9. A drip pan is shown at 12, and is provided with a handle 13 to facilitate its removal and replacement through the opening 11. A jacket or concealing band 14 encircles the container 7, and is in this instance made of wickerwork so as to have the outer appearance of a basket. It is provided at its top with a rim 15 of annular form and having an ornamental appearance. The jacket 14 is further provided, at its bottom edge, with an annular rim 16, also ornamental.

A flower pot 17, of the usual or any desired form, fits neatly into the container 7 and rests upon the floor 9. The flower pot holds a quantity of soil 18, in which a plant or flower 19 may live and grow. The flower pot is so arranged that any water leaking from it finds its way through the vent 10 and into the pan. If desired, the flower pot may be omitted and the container 7 filled directly with a charge of soil in which the plant or flower lives. In this event, as before, the leakage water drops through the vent 10 in the pan.

The internal diameter of the jacket 14 is slightly greater than the external diameter of the container 7, so as to leave a space 14^a, of frusto-conical form, between the jacket and the container. Because of the ornamental appearance of the rims 15 and 16, the base 8 and the space 14^a are rendered less noticeable than would otherwise be the case. Owing to the space 14^a the jacket 14 may be lifted bodily upward a little distance, so that the operator can inspect the pan, and if desired may grasp the handle 13 and remove the pan so as to empty and replace it.

Fig. 2 shows, in dotted lines, the jacket 14 as raised and the pan 12 as partially drawn out. When the pan and the jacket occupy their respective normal positions, as indi-

cated by full lines, the pan is concealed and the device as a whole has the appearance indicated in Fig. 1.

In Fig. 4 I show a jardinière of larger size than the one described with reference to Figs. 1 and 2. The container 20 with its floor 21, vent 22 and slot 23, and also the pan 24 with its handle 25 may have substantially the same form as the analogous parts above described. The flower pot 26 and the base 27 may have the form of the flower pot 17 and base 8. A jacket 28, having the general outer appearance of a basket, is provided with a portion 28^a of substantially 15 cylindrical form and, like the container 20, is secured to the base 27 by aid of fasteners, one of which is shown at 29. The jacket 28 is cut away so as to leave a slot 30, in registry with the slot 23. The two slots 23 and 30, in 20 registry with each other, together constitute an opening or doorway through which the pan 24 may be removed and replaced. An annular member 31, made in this instance of wickerwork, encircles the lower portion 25 of the jacket 28, and may be shifted bodily upward relatively to the same, as indicated by dotted lines in Fig. 4. I designate the annular member 31 as a concealing band, because in its normal position it conceals the 30 pan. The manner in which the pan is inspected, removed or replaced may be understood by a study of the dotted lines in Fig. 4.

In Fig. 5 I show the application of my invention to a still larger jardinière, having here the outward form of a vase. A stand 31 is provided adjacent its upper end with a floor 32 and near its bottom with a second floor 33. At the top of the stand is a crown 34, which encircles the bottom of a flower 10 pot or analogous member 35. A drip tube 36 extends through both floors 32 and 33, and at its lower end communicates with a compartment 37. The drip pan appears at 38, and is provided with a handle 39. The drip 15 pan is normally housed within the compartment 37. A concealing band 40 loosely encircles the lower end of the stand 31, and normally rests upon the supporting surface 6. While it occupies its normal position, it 20 effectively conceals the compartment 37, and the pan therein contained. The operator, in order to inspect, remove or replace the pan,

merely grasps the concealing band 40 and lifts it bodily upward, as will be readily understood from the foregoing description. 55

I do not limit myself to the precise construction here shown, as variations may be made therein without departing from the spirit of my invention.

I claim:—

1. In a jardinière the combination of a body member formed to rest in a predetermined normal position upon a supporting surface and provided with a compartment into which water may leak, a drip pan 65 housed within said compartment in order to catch the water thus leaking thereinto, said drip pan being removable from said compartment while said body member rests in said predetermined normal position upon 70 said supporting surface, and a concealing member normally encircling said body member and hiding both said compartment and said drip pan, said concealing member being movable relatively to said body member 75 while said body member is resting upon said supporting surface, in order to permit the removal of said drip pan without disturbing the position occupied by said body member while resting upon said supporting surface. 80

2. In a jardinière the combination of a body member formed to normally rest in a predetermined position upon a supporting surface and provided with a floor and with a compartment beneath said floor, said floor 85 having means to facilitate the leakage of water through it into said compartment, a drip pan housed within said compartment for the purpose of catching the water thus leaking thereinto, said drip pan being removable from said compartment while said body member is resting upon said supporting surface; and a concealing member loosely encircling said body member and movable relatively thereto in order to promote access to said drip pan, said concealing member normally hiding said compartment and said drip pan, and having such structure as to simulate an integral part of said body member. 90 95

WILLIAM N. REED.

In presence of—

ALEXANDER LEVENE,
JACOB HILLQUIT.
